UNITED STATES PATENT OFFICE.

THOMAS VAN OSTRAND, OF KINSLEY, KANSAS, ASSIGNOR OF TWO-THIRDS
TO FRANK A. COFFMAN AND ADAM TELFER, BOTH OF SAME PLACE.

HANDSAW.

SPECIFICATION forming part of Letters Patent No. 350,403, dated October 5, 1886.

Application filed May 8, 1886. Serial No. 201,566. (No model.)

To all whom it may concern:

Be it known that I, THOMAS VAN OSTRAND, a citizen of the United States, and a resident of Kinsley, in the county of Edwards and State 5 of Kansas, have invented certain new and useful Improvements in Handsaws; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a view of my improved saw. 15 Fig. 2 is a longitudinal sectional view of the same on line $x-x$, Fig. 1. Fig. 3 is a longitudinal sectional view on line $y-y$, Fig. 2; and Fig. 4 is an enlarged detail view of the handle, as shown in Fig. 3.

20 Similar letters of reference indicate corresponding parts in all the figures.

My invention has relation to that class of saws in which one edge is formed with teeth for ripping and the other edge with teeth set 25 for cross-cut; and it consists in the improved construction and combination of parts of such a saw, having an adjustable handle which may be set at different angles with reference to the edges of the saw-blade, allowing the handle to 30 be adjusted conveniently to the different classes of work to be performed by the saw, as hereinafter more fully described and claimed.

In the accompanying drawings, the letter A indicates the saw-blade, one edge, B, of which 35 has its teeth set for ripping, while the other edge, C, has the teeth set for cross cut.

The upper end of the saw is formed with a 40 perforation, D, at the center line of the saw and segmental slots, E E and F are formed in the blade concentric with the perforation, two of the slots being to the sides of the perforation, while the third slot, F, is placed with 45 its middle in a line with the perforation. A bolt, G, passes through the perforation, and through perforations H in the lips of the handle J, which lips bear against the sides of the upper end of the saw-blade, and this bolt, which is formed with a countersunk head, I, at one end, has a countersunk nut, K, at its 50 threaded end, and the bolts L L, which pass through perforations M M in the lips of the

handle sliding in the slots E, are similarly shaped and provided with nuts N. A bolt, O, fits with its polygonal head P in a countersink, Q, in one lip of the handle, and passes through 55 a perforation, R, in the said lip and through the slot F in the saw-blade, and the other lip is formed with a registering perforation having a metallic lining, S, and a tubular washer, T, fitting within it and bearing against the 60 edges of the slot with its inner end. A thumb-nut, U, having a tubular sleeve, V, upon its inner side, fits with the said sleeve, and with its central perforation upon the screw-threaded end of the bolt having a screw-threaded bore, 65 and the sleeve fits within the lined perforation bearing against the outer end of the washer.

It will now be seen that when the thumb-nut is loosened the blade may be rocked, turning upon the pivotal bolt, the bolts in the slots serving as guides, so that the handle may be set at the desired angle to the edge of the saw-blade, and when the thumb-nut is tightened the sleeve of the nut will bear against the 70 outer end of the tubular washer, the inner end of which will bear against the edges of the adjusting-slot, binding the saw-blade in its adjusted position.

It will be seen that the tubular sleeve of the 75 thumb-nut will have two functions—viz., to bear against the washer and force the same against the blade, at the same time guiding the nut and the bolt, and at the same time the sleeve will add to the threaded portion of 80 the nut, giving it more threaded surface, and consequently giving it a firmer and more durable hold upon the screw-threaded portion of the bolt, preventing it from cutting the thread or being placed obliquely upon the threaded 85 portion of the bolt.

Having thus described my invention, I claim and desire to secure by Letters Patent of the United States—

In a handsaw, the combination of a blade 90 having different teeth at its edges and formed with a pivotal perforation in the center line of the blade, and with a concentric slot in a line with it, and formed with concentric segmental slots at the sides of the perforation, a handle 100 having its lips formed with perforations for the admission of bolts for the perforation and

slots, a pivotal bolt and two other nutted and headed bolts fitting in the perforations for the pivotal perforation of the blade and the guide-slots of the blade, a bolt fitting into a counter-sink at one lip of the handle, and having its threaded portion projecting through a metallic-lined perforation in the other lip, a washer inserted in the said perforation around the bolt bearing with its inner end against the saw-blade, and a thumb-nut having a sleeve upon its inner side formed with a threaded

bore, and fitting upon the bolt and inside of the lined perforation bearing against the washer, as and for the purpose shown and set forth.

In testimony that I claim the foregoing as my own I have hereunto affixed my signature in presence of two witnesses.

THOMAS VAN OSTRAND.
